UNITED STATES PATENT OFFICE.

SEWARD HOMER CALKINS, OF FLUSHING, NEW YORK, ASSIGNOR TO THE TRAITEM
MARBLE COMPANY, A CORPORATION OF NEW YORK.

METHOD AND MEANS FOR LAYING CONCRETE FLOORINGS.

Application filed May 19, 1927. Serial No. 192,741.

This invention relates to floorings having a top layer composed principally of cement.

Cement floorings, so called, are constructed of a concrete fill or foundation composed of cinders or other coarse material mixed with sand, and a relatively small percentage of cement, and on that concrete fill or foundation a finishing coat is applied, consisting of a relatively large percentage of cement, mixed with sand.

Heretofore it has been the general custom to spread the material forming the concrete fill and finishing coat in continuous layers, with the result that objectionable cracking takes place in the mass due to the shrinkage thereof.

To overcome the disadvantages of such construction it has been the usual practice to divide the finishing layer of the flooring into sections so that one or more sections may be cut out and replaced without injury to the adjacent sections.

Such practices produce other and new disadvantages.

When the upper layer or finishing coat is so cut through to the under layer or concrete fill, open joints are produced by such cutting and the marginal edges of the respective sections become exposed to the atmosphere and consequently become dried out and shrink before the material forming the main body of the sections has become hardened, and objectionable cracks form on the margins of the sections due to that unequal contraction of the material forming the sections.

Furthermore, the drying out and shrinkage of opposite marginal edges of adjacent sections enlarge the width of the cuttings originally made to divide the finishing layer into sections.

It has been found moreover that the only practical way of finishing the exposed edges of such cutting is to make the cutting in the form of a groove, V-shaped in cross section.

Such grooves and open joints form receptacles for dirt and unsanitary matter of various kinds and also present an unsightly appearance frequently attended with bumps and irregular edges formed on the face of the upper surface of the finishing coat of the flooring, at the grooves.

This invention has for one of its main objects to provide a method and means for constructing cement floorings having many, and

if so desired, all, of the important features of a terrazzo flooring, at a cost of production and maintenance much lower than that of terrazzo, and in which the open joints between the sections of a cement flooring and their many and serious disadvantages are eliminated, and a flooring heretofore used mainly for warehouses, and the roughest kind of use, may be superseded by a concrete flooring suitable for use in the highest class of public buildings, apartment houses, hotels, office buildings, stores, banks, and others of like importance. The invention is designed primarily for use in concrete floorings in which the sections are of the same color.

These and other objects of the invention hereinafter referred to are accomplished in the manner and by the means hereinafter more particularly described, and illustrated in the accompanying drawings, in which similar reference numerals designate corresponding parts throughout the several views, but it is to be understood that changes, alterations and modifications may be made therein without departing from the invention as defined in the claims hereinafter stated.

As illustrated in the drawings—

Figure 1 is a cross section of a cement flooring showing in side elevation a dividing strip used in carrying out the invention.

Figure 2 is a cross section taken on the line 2—2 of Figure 1, and

Figure 3 is a cross section of a cement flooring showing in side elevation a dividing strip of modified construction used for carrying out the invention.

Figure 4 is a perspective view.

In carrying out the invention a foundation, sometimes called a concrete fill, is provided, and may consist of a material ordinarily used for such purposes, such as cinders, broken stone, and sand, mixed with cement.

The material forming the concrete fill or foundation after being thoroughly mixed and wet, is laid while in a semiplastic condition in a continuous layer, and leveled off by any suitable means to form a substantially even surface.

As illustrated in the drawings 1 represents the concrete fill or foundation, and 2 a concrete finishing coat.

The finishing coat is composed as usual of the desired proportions of cement and

sand, thoroughly mixed, and while in a plastic condition is laid in a continuous sheet on top of the concrete fill or foundation while the concrete fill is in a condition sufficiently moist to make a proper adhering connection with the material forming the finishing coat and sufficiently moist or plastic to permit a dividing strip to be pressed through the finishing coat and into said concrete fill or foundation.

After the finishing coat has been laid and while the material thereof is in a plastic condition the surface of that coat is trowelled to compress the material and remove the excess of water contained therein.

The upper surface is marked off by means of lines, straight-edge, pointing trowel or other suitable means to define the pattern or divisions to be made in the flooring.

Dividing strips such as shown in the drawings, or other suitable construction, are then depressed into the finishing coat, and through said coat, into the concrete fill on the lines so marked, until the top edge of the strips is in substantial alignment with the surface of the top coat.

The strips may be pressed into the finishing or top coat and into the underbed by any suitable means, such as shown and described in Letters Patent numbered 1,511,799, issued to me October 14, 1924, having a groove or kerf to receive the upper edge of the strip, and adjacent flanges adapted to compress the material of the top coat underneath said flanges and force said material into the openings 4 of the strip.

The dividing strip 3 shown in Figure 1 herein consists of a flat strip having sides provided with openings 4, between the upper and lower margins of the strip, and the lower margin is provided with anchors 5 preferably connected with an intermediate marginal extension 6 of the body of the strip.

When the strip is depressed into the finishing coat and the concrete fill or foundation of the flooring in the manner stated, with the upper edge of the strip in the horizontal plane of the upper surface of the finishing coat, the anchors 5 and extensions 6 of the strip will be embedded in the concrete fill, and the inclined edges 7 with which the anchors are provided will aid in resisting any upward displacement of the strip.

The openings 4 of the strip will be within the top or finishing coat of the flooring, and the cement of which that coat is composed will extend through the openings 4, which form locks that serve as the main means for holding the strip in place against vertical displacement, at the same time locking adjacent sections of the finishing coat together.

After the strips have been driven into the finishing coat and underbed, the upper sur-

face of the finishing coat is given another trowelling, compressing and leveling off the upper surface, and making a close even connection between the material of the finishing coat and the upper edge of the strips, thereby producing a continuous upper surface unbroken by any scorings or depressions, and displaying the upper edges of said strips, and forming designs or patterns of pleasing and ornamental appearance.

It sometimes happens that the foundation or concrete fill of a flooring is completed and becomes thoroughly dried and hardened before the finishing coat is ready to be applied, consequently the anchors of the pattern strips can not penetrate the hard concrete fill.

In such cases a pattern strip may be used of the character described, without the penetrating anchors 5, as indicated by the dividing strip shown in Figure 3, wherein the lower edge of the strip is supported and rests upon the underbed, and the inclined edges 7 of the marginal extension 6 engage the material forming the finishing coat and aid in preventing any upward displacement of the strip.

What I claim as new is:

1. The method of laying concrete floorings, consisting in providing a foundation of relatively coarse material in a semi-plastic condition, and applying upon said semi-plastic foundation, a top layer composed principally of cement in a plastic condition, then trowelling the top layer to compress the material thereof and remove the excess of water therefrom, then pressing into the top layer and foundation dividing strips having openings therein located in said top layer to permit the material of the top layer to enter, and, when hardened, join adjacent sections of the top layer together, said strips having also anchors that are pressed into the semi-plastic foundation and provided with means for preventing any upward displacement of said strips, and finally subjecting the surface of said top layer to a finishing trowelling.

2. The method of laying concrete floorings, consisting in providing a foundation of relatively coarse material in a semi-plastic condition and applying upon said semi-plastic foundation a top layer composed principally of cement in a plastic condition, then trowelling the top layer to compress the material thereof, and remove the excess of water therefrom, then pressing into the top layer and foundation dividing strips having anchors extending below the body of said strips and into the foundation material, and finally subjecting the surface of said top layer to a finishing trowelling.

3. The method of laying concrete floorings, consisting in providing a foundation of relatively coarse material in a semi-plastic

condition and applying upon said semi-plastic foundation a top layer composed principally of cement in a plastic condition, then trowelling the top layer to compress the material thereof, and remove the excess water therefrom, then pressing into the top layer dividing strips having openings therein to

permit the material of the top layer to enter, and when hardened join adjacent sections of the top layer together, and finally subjecting the surface of said top layer to a finishing trowelling. 10

SEWARD HOMER CALKINS.
